ABSTRACT

Phosphorus-free builders for washing and cleaning agents comprising water-soluble salts of sulfonated low molecular weight polybutadiene are compatible with anionic and nonionic tensides as well as perborate bleaching agents.

20 Claims, No Drawings

**WASHING AND CLEANING AGENT CONTAINING
A SULFONATED POLYBUTADIENE BUILDER
SALT**

BACKGROUND OF THE INVENTION

The present invention relates to washing and cleaning agents containing customary detergents and additives, in combination with a phosphorus-free builder.

It is known that the cleaning power of tensides in washing and cleaning agents is increased by the addition of certain supporting compounds which have no cleansing power in themselves. Such substances are variously known as improvers, surfactants, or builders.

The theoretical basis for the effects of such builders has not been fully clarified in detail; therefore, it is impossible to predict which types of compounds will be suitable as a builder. However, it is generally assumed that a plurality of individual effects determines the special properties of the builders, primarily:

Increase in the cleaning power of tensides; dispersion of dirt in order to avoid redeposition; solubilization and/or emulsification of poorly soluble components; preventing deposition of low-solubility salts, especially of calcium and magnesium salts; buffering acidic substances; regulation of the washing liquor sudsing action; compatibility with other conventional detergent components, specifically with bleaching agents; and a minor corrosive effect. Furthermore, biodegradability has in recent years become recognized as an important property.

Various inorganic, alkaline-acting substances are known as builders, e.g. the alkali bicarbonates, carbonates, borates, phosphates, polyphosphates and silicates.

In the most common washing and cleaning agents, the polyphosphates, especially pentasodium tripolyphosphate (sodium tripolyphosphate), are utilized almost exclusively as detergent building agents. The polyphosphate content in the washing and cleaning agents ranges up to 70% by weight, based on the total mixture, in correspondence with the laundering habits of various countries. However, in spite of their excellent builder properties, the use of phosphates is accompanied by increasingly recognized grave ecological disadvantages. Limnologists have for some years observed with increasing anxiety the eutrophication, i.e. overfertilization, of waters and lakes by an excess concentration of nutrients, resulting in a severe disturbance of the biological balance due to strong algae growth. The consequence is a rapid reduction in oxygen content, primarily at the bottom of the lakes, together with a concomitant increase in decay processes which finally effect the destruction of plant and animal life. In part, detergent phosphates are held responsible for this damage; c.f. Tensides 8 (2); 82 (1971).

Polyphosphates also exhibit practical disadvantages in storage and use, as they are readily hydrolyzed into meta- and ortho-phosphates, which are low-quality builders.

The corrosive properties of the polyphosphates on metals and alloys are another problem, mentioned by K. Lindner, in Tensides — Textile Adjuvants — Laundry Raw Materials, Wissenschaftliche Verlagsgesellschaft mbH, Stuttgart, 1964, Vol. II. pp. 1189 and 1195.

In order to circumvent these and other disadvantages of the polyphosphates, the prior art has proposed several phosphate-free builders for use in washing and

cleaning agents. In the United States, for example, nitrilotriacetate or nitrilotriacetic acid (NTA) was utilized for a time in detergent recipes. However, it has since been found disadvantageous because NTA cannot be readily biodegraded under all commonly encountered conditions. Additionally, the nitrogen interferes as a eutrophication-enhancing factor. Another property of NTA now evoking misgivings is the excellent complexing capacity for heavy metals and transition metals which is particularly undesirable with respect to mercury and arsenic, and which can result in an undesired concentration of these substances. Finally, it was found that NTA and perborate neutralize each other; NTA, with the perborate bleaching agent being consumed, is degraded to form amine oxides and other oxidation products Tensides 8 (1): 2 (1971).

OBJECTS OF THE INVENTION

Accordingly, it is an object of this invention to provide improved detergent building agents.

Another object of this invention is to provide improved phosphate-free detergent compositions.

An additional object of this invention is to provide an improved process for preparing detergent composition.

A further object of this invention is to provide an improved laundering process.

Upon further study of the specification and appended claims, further objects and advantages of this invention will become apparent to those skilled in the art.

SUMMARY OF THE INVENTION

Briefly, the above and other objects are attained in one aspect of this invention by providing in a washing and cleaning composition comprising an anionic or nonionic tenside, the improvement which comprises 10-70% by weight, based on the total weight of the composition, of a water-soluble salt of a 17-100 molar percent sulfonated polybutadiene polymer having a molecule weight prior to sulfonation of 500-10,000.

DETAILED DISCUSSION

The washing agents of this invention are characterized in that they contain as the builder, water-soluble salts of polybutadiene containing sulfonic acid groups wherein the molecular weights of the basic polymers are 500-10,000, preferably 1,500-3,500, and a degree of substitution of the sulfonated polybutadiene of 0.17-1.0, preferably 0.22-0.7, especially 0.33-0.5 molar parts per monomer unit.

The compounds to be employed according to this invention can be prepared in accordance with conventional methods. For example, polybutadienes having average molecular weights of 500 to 10,000 can be produced by polymerization in inert organic diluents in the presence of alkyl aluminum halides and organo-nickel compounds, e.g. nickel acetylacetone. In this connection, it can be advantageous to add minor amounts of electron donors, e.g. ethers or amines. See B.

Schleimer and H. Weber, "Applied Macromolecular Chemistry", 16/17: 253-269 (1971), incorporated by reference herein. The polybutadienes prepared in this manner contain 30-90%, preferably 50-85% 1,4-cis-double bonds, 65-10%, preferably 50-15%, 1,4-trans-double bonds, and 5-0%, preferably less than 1% vinyl double bonds.

The polybutadiene sulfonates of this invention are produced by sulfonation with SO_3 , advantageously uti-

lized in the form of a complex, e.g. an etherate, such as SO_3 -dioxane. The liquid polymer, suitably dissolved in an organic solvent (which can be, if desired, the polymerization solvent), is reacted with 1.0-1.5 mol, preferably 1.25 mol per monomer unit of the polybutadiene, of SO_3 or an SO_3 -complex, at a temperature 25°-30° C. Thereafter, the reaction mixture is neutralized with alkali. After the working-up process, the product is obtained primarily as the alkali salt of the sulfonated polybutadiene, optionally in a mixture with residual alkali sulfate which generally need not be separated for use as the building substances of this invention. Preferred are the sodium and potassium salts.

Although any water-soluble sulfonate of the polybutadienes having the molecular weights of 500-10,000 can be employed as a builder, the alkali salts are preferred, especially the alkali metal salts, i.e. Li, Na, K, Cs, NH_4 , etc. and particularly Na and K.

The builders of this invention are to be used in an amount of 10-70% by weight, preferably 20-60%, especially 35-60% by weight, based on the total mixture of the washing and cleaning agent. The weight ratio of builder to tenside is generally 1:3 to 10:1. They can also be utilized in combination with other builders or can replace a portion of the phosphates in washing agents, but in general are preferably employed as substantially the only builder, i.e. with less than 50%, preferably less than 10% of other builders.

The laundry-active substances and additives are added in the customary quantitative proportions, for example:

	Broad	Preferred	
Laundry-active substance	5 - 30 wt. %	8 - 18 wt. %	35
Sodium perborate	0 - 30 wt. %	0 - 20 wt. %	
Sodium sulfate	0 - 40 wt. %	10 - 30 wt. %	
Soda (sodium carbonate)	0 - 20 wt. %	0 - 7 wt. %	
Silicates	0 - 15 wt. %	0 - 6 wt. %	

The washing and cleaning agents according to the invention can contain one or more of conventional anionic and nonionic detergents and additives; cationic detergents are generally not satisfactory, for laundry purposes, because they are absorbed by the negatively charged textile fibers and so tend to act as soil fixatives. Some cationic detergents may be used, however, in small concentrations as fabric softeners, if the active ingredient is a nonionic detergent.

Suitable anionic tensides include but are not limited to the alkyl sulfonates, alkyl benzenesulfonates, olefin sulfonates, alkyl sulfate, alkyl ether sulfates, alcohol oxyethylates, alkyl phosphates, alkyl ether phosphates, etc.

Suitable nonionic tensides include but are not limited to the alkyl polyglycol ethers, alkyl phenol polyglycol ethers, acyl polyglycol ethers, oxyethylated fatty acid amides, fatty acid polyglycol esters, polyaddition products from ethylene oxide and propylene oxide, etc.

Without further elaboration, it is believed that one skilled in the art can, using the preceding description, utilize the present invention to its fullest extent. The following preferred specific embodiments are, therefore, to be construed as merely illustrative, and not limitative of the remainder of the disclosure in any way whatsoever.

EXAMPLE 1

60 g. of polybutadiene having a molecular weight of

1,500 and a content of 75% 1,4-cis-double bonds, 24% 1,4-trans-double bonds, and less than 1% vinyl double bonds (1.11 mol monomer unit) is dissolved in 1,000 ml. of cyclohexane at 25°-30° C. and mixed within 5 15-20 minutes batchwise with a slurry of a SO_3 -dioxane complex (1.25 mol) in methylene chloride. Thereafter, the mixture is allowed to react another 10 minutes, the acid is vacuum-filtered and the mixture washed with ethanol and neutralized with an aqueous solution of 42 10 g. of sodium hydroxide under cooling. The sulfonate solution is lightened at 70° C. with 75 ml. of 30% hydrogen peroxide and heated to the boiling point for 10 minutes under a reflux condenser. After removing the water in a forced circulation evaporator, 161 g. of polybutadiene sulfonate containing 13.8% sodium sulfate is obtained. The degree of substitution of the thus-sulfonated polybutadiene amounts to 0.42.

The following pertinent recipes of several standard household detergents and gentle detergents will further explain the invention:

EXAMPLE 2

8.0% n-Dodecylbenzenesulfonate
 3.5% Palmityl alcohol oxyethylate (15 mol of ethylene oxide)
 4.0% "Talgolit" soap Sodium-salt of a $\text{C}_{16}-\text{C}_{18}$ carboxylic acid, (iodine no. 1 to 3)
 48.6% Sodium salt of the sulfonated polybutadiene m.w. 1500, produced according to Example 1
 10.7% Sodium sulfate
 1.0% Sodium toluenesulfonate
 1.0% Carboxymethylcellulose (CMC)
 20.0% Sodium perborate · 4 H_2O
 3.0% Sodium silicate
 0.2% Optical brightener

EXAMPLE 3

11.5% α -Olefin sulfonate ($\text{C}_{14}-\text{C}_{18}$)
 3.0% Sperm oil alcohol oxyethylate (25 mol of ethylene oxide)
 60.0% Sodium salts of sulfonated polybutadiene m.w. 1500, produced according to Example 1
 5.5% Sodium silicate
 1.0% Sodium cumenesulfonate
 1.0% Carboxymethylcellulose (CMC)
 17.8% Sodium perborate · 4 H_2O
 0.2% Optical brightener

EXAMPLE 4

16.0% n-Dodecylbenzenesulfonate
 4.0% $\text{C}_{16}-\text{C}_{18}$ - Fatty alcohol oxyethylate (11 mol of ethylene oxide)
 2.5% "Talgolit" soap
 53.2% Sodium salt of sulfonated polybutadiene m.w. 3500, produced according to Example 1
 6.4% Sodium carbonate
 0.7% Sodium chloride
 1.0% Sodium toluenesulfonate
 1.0% Carboxymethylcellulose (CMC)
 15.0% Sodium perborate · 4 H_2O
 0.2% Optical brightener

EXAMPLE 5

18.0% n-Dodecylbenzenesulfonate
 6.8% Palmityl alcohol oxyethylate (15 mol of ethylene oxide)
 3.0% "Talgolit" soap
 45.0% Sodium salt of sulfonated polybutadiene m.w. 1500, produced according to Example 1
 25.0% Sodium sulfate
 1.0% Carboxymethylcellulose (CMC)
 1.0% Sodium toluenesulfonate
 0.2% Optical brightener

0.2%	Optical brightener				

The washing power of the above-mentioned anionic and nonionic detergents is noticeably enhanced by adding the builders of the present invention. Furthermore, these builders retard deposition of the laundry-active substance as salts of low solubility, e.g. calcium salts, so that encrustation of the fabric is prevented. The substances of this invention are further distinguished by a very high suspension power (tested on iron oxide), which represents a measure of dirt-carrying capacity; a very good compatibility with perborate bleaching agents; and a comparatively low corrosive effect with respect to metals.

The builders to be employed according to the invention can thus not only replace the phosphates hitherto mainly used as builders in the washing and cleaning agents, especially pentasodium triphosphate, but also exhibit with respect to these phosphates an improved total property spectrum.

For determining the cleaning power of detergents wherein a proportion of phosphate is replaced by the builders of this invention, test-soiled WFK (Wascherei-Forschunganstalt Krefeld) cotton fabric is washed in a "Launder-Ometer", a standardized laboratory washing machine (Atlas Electric Co., Chicago, Illinois) in an aqueous bath at 90° C. for 30 minutes. For the washing tests, a drinking water of 12° d German hardness (1° d = 0.357 alkaline earth ions mval/l. or 17.8 ppm. of $CaCO_3$; DIN 53910) is employed. By comparison with both the test-soiled unwashed fabric and the unsoiled fabric, the percent washing value is calculated according to the following equation:

$$\% \text{ Washing Value} = a - b/c - b \cdot 100$$

wherein

a = reflectance of the washed fabric

b = reflectance of the test-soiled fabric

c = reflectance of the unsoiled fabric

The reflectance is a measure of brightening caused by the washing process and is measured at 570 μ m on the dried and pressed fabric using a Zeiss "Elrepho" photometer with a R 57 filter which is calibrated against the standard No. 20707. The percent washing value is reported as the average of 24 single measurements on the test fabrics.

In order to further explain this invention and the advances in the art attainable thereby, the following examples and results of experiments will be set forth:

EXAMPLES 7-9

In the following compilation, the percent washing values are indicated obtained with 1 g./l. of sodium dodecylbenzenesulfonate as the laundry-active substance (LAS) and 1 or 2 g./l. of builder in the washing liquor. The values were determined after each of three consecutive washing cycles.

5	Ex.	% Washing Values	Washing Cycles		
			1.	2.	3.
	7	1 g./l. Pentasodium triphosphate (for comparison)	29	39	45
		2 g./l. Pentasodium triphosphate (for comparison)	30	42	48
10	8	1 g./l. Na salt of sulfonated polybutadiene (molecular weight 1500), produced analogously to Example 1	16	35	46
		2 g./l. Na salt of sulfonated polybutadiene (molecular weight 1500), produced analogously to Example 1	27	43	52
20	9	1 g./l. Na salt of sulfonated polybutadiene (molecular weight 3500), produced analogously to Example 1	12	32	41
		2 g./l. Na salt of sulfonated polybutadiene (molecular weight 3500), produced analogously to Example 1	17	37	48

EXAMPLES 10-12

25 For determining hardness stability, variously concentrated solutions of sodium dodecylbenzenesulfonate and builder are examined for turbidity in water samples having varying hardness values. From a series of measurements, a total value is then derived, which can range between 15 for poor hardness stability and 75 for very good hardness stability. According to a certain key, stability values can be determined therefrom, on a scale of from 1 to 5. Details of this test can be found in DIN 30 53 905. In the ideal case of maximum insensitivity with respect to hardening agents in the water, this value is 35 5. As can be seen from the following compilation, the builders of the present invention in conjunction with sodium dodecylbenzenesulfonate clearly show a better 35 hardness stability than pentasodium triphosphate.

TABLE II

45	EX.	Builder	Hardness Stability According to DIN 53 905	
			Stability Value	Total Value
	10	Pentasodium triphosphate (for comparison)	3	37
	11	Na salt of sulfonated polybutadiene 1500, produced analogously to Example 1	4	57
	12	Na salt of sulfonated polybutadiene 3500, produced analogously to Example 1	4	63

55 In all further examples, builders of this invention were used which were produced in accordance with Example 1.

EXAMPLES 13-5

60 The compatibility of the builders of this invention with the remaining components of the detergent was examined with sodium perborate, frequently employed as a bleaching agent. Perborate stability was evaluated by first determining iodometrically the active oxygen content of a 0.004 mol/l. solution of perborate in distilled water without the addition of foreign substances, and assigning this active oxygen content a value of 65 100%. Thereafter, a solution containing 0.004 mol/l.

perborate, 0.004 mol/l. of builder and 10 mg./l. of iron (III) chloride was heated to 90° C., and the decreasing active oxygen content was measured after 30, 60, and 150 minutes. The thus-obtained values were related to the comparison solution value of 100%. The results demonstrate the increased stabilizing effect of the builders of the present invention in comparison to phosphate with respect to perborate.

TABLE III

Ex.	Builder	% Active Oxygen After		
		30 min.	60 min.	150 min.
13	Pentasodium triphosphate (comparison)	29.0	15.5	4.5
14	Na salt of sulfonated polybutadiene m.w. 1500	66.0	55.0	36.0
15	Na salt of sulfonated polybutadiene m.w. 3500	65.0	57.5	43.0

EXAMPLES 16-18

One measure of the dirt-carrying capacity of a builder is its suspending power, e.g. with respect to pulverized iron oxide. For this purpose, a testing method was devised wherein pulverulent red Fe_2O_3 with a specific surface of 15.7 m^2/g (commercial available as "Oxidrot AKF" from Sigle, Stuttgart (W.-Germany) is shaken intensively for one minute in a vibrating cylinder with an aqueous solution of the builder and sodium dodecylbenzenesulfonate. 24 Hours later the magnitude of the remaining turbidity is determined by photometry. The relative values obtained by measuring the extinction coefficients indicate the suspending power of the builders, wherein values from 100 upwards are denoted as "good".

TABLE IV

Ex.	Builder	Extinction Coefficient in 1 cm. layer thickness
16	Pentasodium triphosphate (comparison)	160
17	Na salt of sulfonated polybutadiene, m.w. 1500	211
18	Na salt of sulfonated polybutadiene, m.w. 3500	129

EXAMPLES 19-21

The procedure used to determine the corrosive properties of the builders of this invention with respect to steel was as follows: Degreased steel sheets made of St 37 (DIN 17,100) were arranged in a glass flask with a reflux condenser attached overhead so that the sheets were immersed halfway in a 5% aqueous solution of the builder substances adjusted to a pH of 10. The solution was alternately boiled under reflux for 8 hours and left at room temperature for 16 hours. During the latter period, air could gain access to the test sheets. After 8 days, the resultant adhering rust was detached by a 30-minute immersion in 2N hydrochloric acid containing 0.25% lauryldimethylbenzylammonium chloride. Thereafter, the test sheets were sequentially washed with water, acetone and benzene, and then dried. The total weight loss incurred by the sheets during the treatment, corresponding to the amount of iron corroded, was determined. As can be seen from the following

compilation, pentasodium triphosphate exhibits a far stronger corrosive effect than the builders of this invention.

TABLE V

Ex.	Builder	Corrosion in g./m ²
19	Pentasodium triphosphate (comparison)	61.4
20	Na salt of sulfonated polybutadiene m.w. 1500	22.1
21	Na salt of sulfonated polybutadiene m.w. 3500	23.8

The above examples demonstrate the high-quality washing and cleaning agents are obtained using the builders according to the present invention.

The preceding examples can be repeated with similar success by substituting the generically or specifically described reactants and/or operating conditions of this invention for those used in the preceding examples.

From the foregoing description, one skilled in the art can easily ascertain the essential characteristics of this invention, and without departing from the spirit and scope thereof, can make various changes and modifications of the invention to adapt it to various usages and conditions.

What is claimed is:

1. In a washing and cleaning composition comprising an anionic or nonionic tenside, the improvement which comprises 10-70% by weight, based on the total weight of the composition, of a builder comprising a water-soluble salt of a 17-100 molar percent sulfonated polybutadiene polymer having a molecular weight prior to sulfonation of 500-10,000.

2. A composition according to claim 1, wherein said polybutadiene contains 30-90% cis-1,4 double bonds, 65-10% trans-1,4 double bonds and less than 5% vinyl-1,2 double bonds.

3. A composition according to claim 2, wherein said molecular weight is 1,500-3,500.

4. A composition according to claim 2, wherein said polybutadiene is 22-70 molar percent sulfonated.

5. A composition according to claim 4, wherein said polybutadiene contains 50-85% cis-1,4 double bonds, 50-15% trans-1,4 double bonds, and less than 1% vinyl-1,2 double bonds.

6. A composition according to claim 5, wherein said polybutadiene is 33-50 molar percent sulfonated.

7. A composition according to claim 6, wherein said polybutadiene builder is present in an amount of 20-60 weight %.

8. A composition according to claim 7, wherein the ratio of builder to tenside is about 1:3 to 10:1.

9. A composition according to claim 1, wherein said water-soluble salt is an alkali metal salt.

10. A composition according to claim 9, wherein said composition is substantially free of builders other than said polybutadiene.

11. A composition according to claim 1, consisting essentially of 5-30 weight % of said tenside, said builder, 0-20 weight % sodium perborate, 0-40 weight % sodium sulfate, 0-20 weight % sodium carbonate and 0-15 weight % silicates.

12. A composition according to claim 11, wherein said tenside is an anionic tenside selected from the group consisting of alkyl sulfonates, alkyl benzenesulfonates, olefin sulfonates, alkyl sulfates, alkyl ether sul-

fates, alcohol oxyethylate sulfates, alkyl phosphates and alkyl ether phosphates.

13. A composition according to claim 11, wherein said tenside is a nonionic tenside selected from the group consisting of alkyl polyglycol ethers, alkyl phenol polyglycol ethers, acyl polyglycol ethers, oxyethylated fatty acid amides, fatty acid polyglycol esters and poly-addition products from ethylene oxide and propylene oxide.

14. A composition according to claim 11, consisting essentially of:

8.0% n-Dodecylbenzenesulfonate
3.5% Palmityl alcohol oxyethylate (15 mol of ethylene oxide)
4.0% Sodium salt of a C_{16} - C_{18} carboxylic acid having an iodine number of 1-3
48.6% Sodium salt of sulfonated polybutadiene having a molecular weight prior to sulfonation of 1500
10.7% Sodium sulfate
1.0% Sodium toluenesulfonate
1.0% Carboxymethylcellulose (CMC)
20.0% Sodium perborate · 4 H_2O
3.0% Sodium silicate
0.2% Optical brightener.

15. A composition according to claim 11, consisting essentially of:

11.5% α -Olefin sulfonate (C_{11} - C_{18})
3.0% Sperm oil alcohol oxyethylate (25 mol of ethylene oxide)
60.0% Sodium salt of sulfonated polybutadiene having a molecular weight prior to sulfonation of 1500
5.5% Sodium silicate
1.0% Sodium cumenesulfonate
1.0% Carboxymethylcellulose (CMC)
17.8% Sodium perborate · 4 H_2O
0.2% Optical brightener.

16. A composition according to claim 11, consisting essentially of:

16.0% n-Dodecylbenzenesulfonate
4.0% C_{16} - C_{18} - Fatty alcohol oxyethylate (11 mol of ethylene oxide)
2.5% "Talgolit" soap
53.2% Sodium salt of sulfonated polybutadiene having a molecular weight prior to sulfonation of 3500
6.4% Sodium carbonate
0.7% Sodium chloride
1.0% Sodium toluenesulfonate
1.0% Carboxymethylcellulose (CMC)
15.0% Sodium perborate · 4 H_2O

0.2% Optical brightener.

17. A composition according to claim 11, consisting essentially of:

5
18.0% n-Dodecylbenzenesulfonate
6.8% Palmityl alcohol oxyethylate (15 mol of ethylene oxide)
3.0% "Talgolit" soap
45.0% Sodium salt of sulfonated polybutadiene having a molecular weight prior to sulfonation of 1500
25.0% Sodium sulfate
1.0% Carboxymethylcellulose (CMC)
1.0% Sodium toluenesulfonate
0.2% Optical brightener.

15 18. A composition according to claim 11, consisting essentially of:

20
16.0% α -Olefin sulfonate (C_{14} - C_{18})
5.6% Palmityl alcohol oxyethylate (15 mol of ethylene oxide)
3.9% "Talgolit" soap
57.5% Sodium salt of sulfonated polybutadiene having a molecular weight prior to sulfonation of 1500
13.0% Sodium sulfate
1.0% Sodium toluenesulfonate
1.8% Sodium carbonate
1.0% Carboxymethylcellulose (CMC)
0.2% Optical brightener.

19. A process for preparing washing and cleaning agents containing a phosphorus-free builder which comprises:

30
a. sulfonating a polybutadiene having a molecular weight of 500-10,000 and containing 30-90% cis-1,4 double bonds, 65-10% trans-1,4 double bonds and less than 5% vinyl-1,2 double bonds with a sulfonating agent selected from the group consisting of sulfur trioxide and sulfur trioxide complexes to form a 17-100 molar % sulfonated polybutadiene;
b. neutralizing the resultant reaction mixture with an alkali solution whereby an alkali sulfate is formed; and
c. adding the resultant sulfonated polybutadiene and alkali sulfate without separation thereof as a phosphorus-free builder to a washing and cleaning agent comprising an anionic or nonionic tenside.

35
40
45
20. In a process for laundering textiles, the improvement which comprises using as the washing and cleaning agent the composition according to claim 1.
